UNITED STATES PATENT OFFICE.

EMIL F. DE WITT, OF LANSINGBURG, NEW YORK.

SANDING DEVICE FOR STREET-CARS.

SPECIFICATION forming part of Letters Patent No. 498,632, dated May 30, 1893.

Application filed February 27, 1893. Serial No. 463,856. (No model.)

To all whom it may concern:

Be it known that I, EMIL F. DE WITT, a citizen of the United States, residing at Lansingburg, county of Rensselaer, and State of New York, have invented certain new and useful Improvements in Sanding Apparatus for Railway-Cars, of which the following is a specification.

My invention relates to such improvements and consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

Figure 1 of the drawings is a vertical longitudinal section of a portion of a car showing my improved sanding apparatus in side elevation attached to the car. Figs. 2 and 3 are respectively side and rear views in plan of the tube-supporting segment made in one piece with the tube-cap and valve-actuating lever, detached. Figs. 4 and 5 are respectively side-edge, and end-edge views of the tube-supporting spring, detached. Fig. 6 represents a horizontal section of the spring taken on the broken line 6—6, in Fig. 3. Fig. 7 is a view in side elevation of the flexible tube, detached. Fig. 8 is a view in side elevation of the sand-hopper with a portion of the car-bottom in section, and showing in longitudinal section a supply-tube having a lateral offset and rotatively secured to the hopper. Fig. 9 is a plan view of the upper end of the supply-tube having a lateral offset.

The subject-matter of this application is an improvement upon the sand-box shown and described in United States Letters Patent No. 491,161, issued to me February 7, 1893, to which Letters Patent reference may be had in connection with the following description.

Referring to the drawings, A— is an end platform of the car, and A'— the dashboard. The sand-hopper A²— is secured in an aperture in the car floor by bolts A³— passing through the floor and a flange A⁴— on the hopper. The outlet at the lower end of the hopper is provided with a flexible supply-tube B— of rubber or other suitable material,

like those in common use, leading to the track-rail A⁵— to convey sand from the hopper to the rail.

It is well known that at certain seasons of the year in freezing climates, mud and partly melted snow or ice will adhere to and freeze upon such supply-tubes until, as frequently happens, the mouth of the tube becomes closed, which renders the sanding-apparatus useless. One of the objects of my invention is to provide means for swinging the tube upward and securing it in a position of safety. Such means comprise a link or links B'— connected at one end with the lower end of the tube, and at the opposite end by the chain B²— with a hook B³— adapted to engage with a catch or stop B⁴— on the dashboard. The chain preferably passes up through an aperture B⁵— in the platform, and the hook through an aperture in the dash, as shown. Any known equivalent means may be employed to swing upward and support the lower end of the flexible supply-tube.

To prevent the tube from making a short bend which would tend to break it, I provide a curved support or segment C— against which the tube is drawn, and supported in the curved position shown in Fig. 1. The segment is preferably made integral with the rock-lever C'— which is linked to and actuates the hopper-valve indicated by dotted lines and marked C²—. This rock-lever is fixed upon the rock-shaft C³— which has its bearings in hangers C⁴— bolted to the platform timbers C⁵—. This rock-shaft is provided with a rock-lever C⁶—, which is connected by link C⁷— to the hand-lever C⁸— fulcrumed upon the car-platform, which hand-lever serves to operate the hopper-valve. The segment piece is also provided with a disk C⁹— which serves as a cap to wholly close the mouth of the flexible tube when the latter is drawn against the cap, as shown in Fig. 1. The disk being integral with the segment and rock-lever C'— also serves as a stop to prevent the operation of the hopper-valve by the hand-lever, when the flexible tube is swung up against such stop or cap. Should a careless operator forget to drop the swinging end of the tube when he desires to sand the track-rail, his inability to work the hand-lever and hopper-valve will call his attention to the

fact that the tube is not in position for use, and he will at once release the tube. By having the supporting segment connected with the valve-controlling mechanism, substantially as shown and above described, movements of such valve-controlling mechanism will effectually separate the tube from its supporting segment, should it freeze thereon or for other reasons adhere thereto after the hook B^3 — is released, thereby allowing a sufficient drop of the discharging end of the tube to effectually deliver sand to the rail.

As an auxiliary device for forcing and maintaining the flexible tube in the most favorable position for delivering sand upon the rail, I provide a spring S — preferably provided at its upper end with a clip S' — which passes around the upper end of the tube and clamps it upon the inserted lower end of the hopper, being secured by a bolt S^2 — passing through the bolt-apertures S^3 — in the clip. The lower end of the spring is also provided with a similar clip S^4 — which incloses the lower end of the tube and affords a convenient means for attaching the links B' — by pivots S^5 — passing through the links and clip. The spring being comparatively wide measured transversely of the rail, and narrow or thin measured longitudinally of the rail, effectually prevents any lateral displacement of the mouth of the tube, laterally of the rail, and assists in straightening the tube after it has been bent into the position shown in Fig. 1. The spring would also serve to prevent the tube from assuming an angular position when swung up from the rail even if the segment was broken off.

It sometimes happens that electric motor cars are so organized and arranged that the mechanism comprising truck-frame and connections, brakes, motors and connections, occupy all available space beneath the floor of the car which is in vertical plane with either of the track-rails. To meet such emergencies, I provide a section of a supply-tube having a lateral offset and means for securing and rotatively adjusting the section upon the hopper, so that the lower end of the tube-section will be in vertical plane with the rail whether the hopper is in such plane or a considerable distance from it on either side.

The tube-section is marked C —, and its offset C' —. The upper end of the section is provided with two oppositely located inwardly projecting lugs, C^2 — adapted to engage with a peripheral annular flange C^3 — on the lower end of the hopper surrounding the hopper-outlet. The flange is cut away on opposite sides, as shown at C^4 — in Fig. 8, to form openings that will just allow the lugs C^2 — on the tube-section to pass up through them when the section is slipped onto the lower end of the hopper. After the lugs have passed

through the openings, the section can be rotated until the lower offsetting end of the section is in vertical plane with the rail. When the section has been rotatively adjusted as desired, it can be fixed in such position by the set-screw C^5 —. When the offsetting tube-section is employed, the flexible supply-tube is secured to the lower end of the section.

What I claim as new, and desire to secure by Letters Patent, is—

1. In a sanding apparatus for railway-cars, the combination with a sand-hopper, of a flexible supply-tube leading downwardly from the hopper, a tube-supporting spring for maintaining the tube in vertical plane with the rail, and means for swinging the lower ends of the tube and spring upwardly, substantially as described. 75

2. In a sanding apparatus, the combination with a sand-hopper and flexible supply-tube leading downwardly from the hopper, of a tube-supporting segment, and means for swinging the tube upwardly against the segment, substantially as described. 80

3. In a sanding apparatus, the combination with a sand-hopper and flexible supply-tube leading downwardly from the hopper, of a cap supported independently and on one side of the tube, and means for swinging the mouth of the tube up against the cap, substantially as described. 90

4. In a sanding apparatus, the combination with a sand-hopper, hopper-controlling valve, mechanism for actuating the valve, and a flexible supply-tube leading downwardly from the hopper, of an oscillatory tube-supporting segment, connections between the segment 100 and valve-controlling mechanism, and means for swinging the tube upwardly against the segment, substantially as described. 95

5. In a sanding apparatus, the combination with a sand-hopper, of a downwardly leading supply-tube rotatively secured to the hopper and provided with a lateral offset, and means for adjustably securing the tube in a fixed position relatively to the hopper, substantially as described. 105

6. In a sanding apparatus for railway-cars, the combination with a sand-hopper, hopper-controlling valve, mechanism for actuating the valve, and a flexible supply-tube leading downwardly from the hopper, of a stop on the valve-controlling mechanism, and a link-connection between the lower end of the tube and the car-frame for holding the tube in a fixed position against the stop, substantially as described. 115

In testimony whereof I have hereunto set my hand this 23d day of February, 1893.

E. F. DE WITT.
